UNITED STATES PATENT OFFICE.

WILLIAM J. SMITH, OF EAST ST. LOUIS, ILLINOIS.

HEATING-STOVE.

SPECIFICATION forming part of Letters Patent No. 781,309, dated January 31, 1905.

Application filed March 8, 1904. Serial No. 197,196.

To all whom it may concern:

Be it known that I, WILLIAM J. SMITH, a citizen of the United States, residing at East St. Louis, St. Clair county, Illinois, have invented 5 certain new and useful Improvements in Heating-Stoves, of which the following is a specification containing a full, clear, and exact description, reference being had to the accompanying drawings, forming a part hereof.

10 My invention relates to downdraft heating-stoves; and it consists in the novel construction hereinafter described and claimed.

The object of my invention is to provide an improved downdraft heating-stove which shall 15 be especially adapted for use in burning soft coal, which shall have greater heating capacity and more perfect combustion and consumption of smoke than ordinary heating-stoves now in use.

20 In the drawings, Figure 1 is a perspective view of a stove embodying my invention. Fig. 2 is a sectional plan view, the section being taken on the line 2 2 of Fig. 1. Fig. 3 is a sectional elevation, the section being taken 25 on line 3 3 of Fig. 4. Fig. 4 is a vertical section on the line 4 4 of Fig. 3. Fig. 5 is a sectional plan view, the section being taken on the line 5 5 of Fig. 4.

The stove is preferably formed in three 30 wide sections 1, 2, and 3, all of the same width, and the central section 2 contains the fire-pot 4, its common shaking-grate 5, and a suitable lining 6 for the walls of the central section, while the outer sections 1 and 3 are located 35 one upon one side of the said central section and the other upon the opposite side of said central section, with a considerable air-space 7 between the walls of the central section and the said outer sections.

40 I have found that a rectangular shape economizes room, as it is adapted to be placed very close to the wall, like a common steam-radiator, the draft-pipe 8 projecting from the top, so that it is not in the way.

45 The stove may be made of either cast or sheet metal and is provided with an upper horizontal chamber 9 and a lower horizontal chamber 10.

The upper and lower horizontal chambers

9 and 10 are connected at their ends by the 50 side chambers 1 and 3, the ends of which latter open into said two horizontal chambers.

The draft-pipe 8 is fitted to a collar 11, located centrally of the upper horizontal chamber. 55

Located centrally in the upper wall of the central chamber 2 is a direct-draft passage 12, which is controlled by a common sliding damper 13, having a handle 14, which projects upon the exterior of the stove at the front. 60

15 indicates the fuel-door, which is hinged to the front of the central section 2 at a point some distance above the upper edge of the lining 6.

16 indicates a common rotary valve or damper for controlling the entrance of air to the central chamber 2, and the said rotary valve is preferably mounted in the front of said chamber over an opening 17, and upon the inner face of said central chamber over said 70 opening is a perforated air-distributer 18, which is shown U-shaped in cross-section and extending in a horizontal direction almost completely across the front of said central chamber. 75

The fire-pot 4 is shown oval in plan view, while the lining 6 above it is arranged in rectangular form. The corners between the lower edge of said lining and the upper edge of said fire-pot are filled by triangular projections 19, formed upon the upper edge of the fire-pot. 80

Located within the lower horizontal chamber 10 beneath the fire-grate 5 is a common removable ash-pan 20, which is provided in 85 its front with a common rotary valve or damper 21.

The side chambers 1 and 3, it will be observed, are very wide, having, in fact, the same width as has the central chamber, which contains the fire-pot 4. 90

I do not herein confine myself to the specific construction of details illustrated in the drawings, as it is obvious that the same may be varied by skilled workmen without departing 95 from the scope of my invention.

The operation is as follows: Fire being started in the fire-pot 4, the products of com-

bustion thereof should be at first permitted to pass directly to the pipe 8 by uncovering the direct-draft opening 12 and air will then be drawn into the ash-pan 20 by way of the 5 damper 21, and said air will pass upwardly through the grate 5, and an updraft will be established through the fire-pot and the central chamber 2. After the fire has been properly started the damper 13 is manipulated by 10 means of its handle 14, and the direct-draft opening 12 is closed, which will cause the products of combustion to reverse their former movement, and air will then be drawn into the central chamber through the rotary damper 16 15 and the air-distributer 18 and will pass downwardly in the central chamber and equally through the fuel within the fire-pot, and also equally past all points of the periphery of the fire-grate 5, and will then pass into the lower 20 horizontal chamber 10 and thence into the side chambers 1 and 3 and pass upwardly therein, and thence into the upper horizontal chamber 9, and, finally, the products of combustion will make their exit through the pipe 8. Fire will 25 pass downwardly in substantially equal volumes at diametrically opposite peripheral points of the fire-grate 5 by reason of the fact that the side chambers 1 and 3 are of such big width that the fire is drawn equally past the 30 periphery of the fire-grate at all points therein, which of course could not be the case if said side chambers were narrower than the fire-pot or narrower than the diameter of the fire-grate, as in the latter case the fire would 35 necessarily be concentrated at the small points

at which the narrow outlet-pipes were connected.

I should have stated that the damper 21 in the front of the ash-pan should be closed while the stove is operating as a downdraft-stove, 40 except when it is desired to keep fire over night, when the said damper 21 may be opened and the damper 16 closed.

I desire to define the word "depth" as found in the following claim as meaning the width 45 of the edge of the stove as distinguished from the width of the front thereof.

What I claim is—

The improved downdraft heating - stove, comprising a central chamber, side chambers 50 approximately of the depth of the central chamber and separated therefrom with a free air-space between them, upper and lower chambers in communication with the central chamber and the side chambers, a smoke-pipe connection applied to the upper chamber, a direct-draft passage from the central chamber to the upper chamber, a damper therefor, means for admitting air for combustion to the central chamber, above the fuel, a grate in the central chamber, and means for admitting air below 55 the grate.

In testimony whereof I have signed my name to this specification in presence of two subscribing witnesses.

WILLIAM J. SMITH.
